Joe. Bello Jr.
WITNESS:

UNITED STATES PATENT OFFICE.

PASQUALE GIANNONE, OF NORRISTOWN, PENNSYLVANIA.

TOP-TORPEDO-FILLING MACHINE.

Application filed January 2, 1923, Serial No. 610,241. Renewed August 6, 1925.

To all whom it may concern:

Be it known that I, PASQUALE GIANNONE, subject of the King of Italy, residing at Norristown, in the county of Montgomery and 5 State of Pennsylvania, have invented new and useful Improvements in Top-Torpedo-Filling Machines, of which the following is a specification.

This invention relates to torpedo filling 10 machines and is particularly directed to machines for filling paper torpedoes which are used at Fourth of July celebrations and the like.

The principal object of the device is to 15 provide mechanical means whereby a large number of torpedoes may be simultaneously filled and may be equally charged with the several ingredients.

Another object is to produce a device of 20 this nature which shall be simple of construction, consisting of few parts, easy to manufacture and assemble, and highly efficient in operation for the purposes for which it is designed.

25 With these and other objects in view as will be more apparent, the invention consists in certain novel construction and combination and arrangement of parts, the essential features of which are hereinafter 30 fully described, are particularly pointed out in the appended claims, and are illustrated in the accompanying drawing, in which:—

Figure 1 is a front elevation of my improved torpedo filling machine.

35 Figure 2 is a vertical transverse section of the same taken on line 3—3 in Fig. 1.

Figure 3 is an enlarged fragmentary section of the same.

Like characters of reference refer to like 40 parts in all the views.

Referring to the drawing in detail, 10 represents a base, 11 the uprights and 12 the cross-piece of a main framework which may be of wood or any other suitable substance. 45 Rotatably mounted in the uprights 11 is a shaft 13, one end of which is formed into a crank 14 and the other end of which is provided with a toothed wheel 15 with which a pawl 16 is adapted to engage for preventing rotation of said shaft. A cord 50 or cable 17 is secured to the shaft 13 and adapted to be wound thereon. One end of the cord or cable 17 is secured to a frame 18, the side members of which slide up and 55 down in grooves 19 formed in the uprights

11, and which carry at their lower ends, cleats or lugs 20 for a purpose which will hereinafter be described.

Removably supported by the base 10 is a 60 box or receptacle 21 and removably mounted on the cleats 20 is a frame 22 having downwardly projecting nipples 23. A plate 24 is shown as removably seated on top of the plate 22. The paper casings of the torpedoes which are being filled are indicated 65 by the numeral 25.

The operation of the device is as follows:—The casings 25 having been previously formed are placed upon the nipples 23 with the frame 18 in an elevated position. 70 The box or receptacle 21 is then placed on the base 10 and the shaft 13 is operated so as to lower the frame 22 until the casings 25 touch the bottom of the box 21. The gravel or small pebbles which are used in the torpedoes are then brushed over the plate or frame 22 until the nipples 23 are filled. The plate 24 is then placed on the plate 22, and it is to be noted, that the apertures 26 in plate 24 are slightly smaller than the apertures in 75 plate 22. The powder and percussion cap are then placed in the apertures 26, these apertures and the plate 24 being properly proportioned to exactly measure the amount of powder required. The handle 14 is then 80 operated to raise the plates 22 and 24 and the weight of the pebbles and powder will cause the paper caps or receptacles to slip off the nipples 23 and to remain in the receptacle or box 21 when the top of the torpedoes may be turned over and pasted.

85 While I have described what I deem to be the most desirable embodiment of my invention, I do not limit myself to the specific details of construction or material, nor to anything less than the whole of my invention as defined in the appended claims.

90 What I claim is:

1. In a device of the class described, the combination of a framework, a receptacle 100 mounted in said framework, a vertically movable device mounted in said framework, a plate mounted on said vertically movable device and formed with a plurality of nipples on its lower face, a second plate removably supported by the first said plate and adapted to measure one of the ingredients, and means for operating said device to raise both of said plates as and for the purpose 105 set forth. 110

2. A torpedo filling machine comprising uprights, a receptacle carried by said uprights adjacent their lower ends, a frame movable vertically along said uprights, a plate carried by said frame and having a plurality of tubular nipples carried thereby, a measuring plate mounted upon said first named plate and provided with measuring

openings aligning with the bores of said nipples, a shaft, a flexible member connecting said frame and shaft for raising and lowering the frame upon rotation of the shaft.

In testimony whereof I affix my signature.

PASQUALE GIANNONE.
